Attorney

UNITED STATES PATENT OFFICE

THEODORE BIRKENMAIER, OF ST. LOUIS, MISSOURI, ASSIGNOR TO W. N. MATTHEWS CORPORATION, OF ST. LOUIS, MISSOURI, A CORPORATION OF MISSOURI

SWITCH

Application filed January 21, 1929. Serial No. 333,841.

This invention relates to switches, and with regard to certain more specific features to means for aligning switch terminal engaging elements with switch terminals.

5 Among the several objects of the invention may be noted the provision of an exceedingly simple method of effecting the alignment above referred to, but at the same time permitting ready removal of the terminal engaging means from the switch unit. Other objects will be in part obvious and in part pointed out hereinafter.

The invention accordingly comprises the elements and combinations of elements, features of construction, and arrangements of parts which will be exemplified in the structure hereinafter described, and the scope of the application of which will be indicated in the following claims.

20 In the accompanying drawings in which is illustrated one of the various possible embodiments of the invention,

Fig. 1 is a cross section showing a fuse switch viewed from the front, the view being 25 taken on line 1—1 of Fig. 2;

Fig. 2 is a cross section taken on line 2—2 of Fig. 1; and

Fig. 3 is a fragmentary detail section illustrating the invention per se.

30 Similar reference characters indicate corresponding parts throughout the several views of the drawings.

Referring now more particularly to Fig. 1, there is illustrated at numeral 1 a housing 35 within which line terminals 3 are supported by suitable insulating means. These terminals include spring terminal clips 5.

Below the bottom 7 of the box 1 and within a pocket 9 is supported the stationary element of a hinge 13, said hinge including a hinged or swingable socket 15 adapted to loosely receive a switch or fuse cartridge 17, the latter including suitable terminal engaging elements or knives 19. The socket 40 is provided with a spur 20 for engagement with the stationary element of the hinge, thus serving to limit the socket movement such that the cartridge mounted therein will not fall out when pulled open. The purpose 45 of this construction is to provide means

whereby the switch cartridge 17 may be manually placed in the socket and then swung upwardly on and with the hinged socket through an opening 21 in the bottom of the box 1 until the terminal engaging 55 elements 19 engage with the line terminals 3. A stop 23 is forced over the lower end of the cartridge to correctly limit the position of the cartridge so that the terminal engaging elements thereof properly strike the line terminals when the switch is closed. The stop 23 also holds the tubes 25 of the cartridge together. 60

It should be noted the cartridge 17 has the tubes 25 thereof usually formed of insulating material such as fibre. The reason for the loose fit of the cartridge 17 in the socket 15 is that the fibre has a tendency to swell or change shape under different weather conditions and it is important that it be not allowed to bind in the socket. The cartridge should at all times be readily removable so that fuse replacements or the like may readily be made. Therefore the socket is made 70 large so that the lower fibrous end of the cartridge fits loosely therein, whereby it may be readily applied and removed even after weather conditions have enlarged the tube. On the other hand it should be noted that the loose fit has resulted in relatively poor alignment between the terminal engaging elements and the line terminals, so that in driving the cartridge into engagement, some degree of care was required to be exercised or there was danger of missing the line terminals with the terminal engaging elements. 75

In order to eliminate the above difficulty, I provide a lug 27 extending upwardly from the hinged socket portion 15. I also provide a recess 29 in the stop 23 to engage with said lug 27. The lug and the stop are composed of metal so that the recess and lug may be given a close or snug fit. The result of this construction is that the loose fit between the lower end of the cartridge and the socket may be retained, but when the cartridge is applied to the socket, engagement between the metallic lug and the recess 29 maintains the cartridge in substantial alignment for throwing it into engagement with 95 100

the line terminals. At the same time there is no danger of binding of the cartridge in the socket 15 or at the recess 29 and it is rendered readily removable.

5 A further safeguard is effected by providing guiding horns 31 on the stationary element of the hinge 13. When the switch is closed, the horns 31 are positioned just above the stop 23 so that the cartridge is positively held in position upon blowing out the fuse 33 therein. The horns also guide the cartridge into engaging position as it is thrown thereto.

15 It is to be understood that the above construction is applicable to any switches per se which involve a similar problem, whether with or without a fuse link.

20 In view of the above, it will be seen that the several objects of the invention are achieved and other advantageous results attained.

25 As many changes could be made in carrying out the above constructions without departing from the scope of the invention, it is intended that all matter contained in the above description or shown in the accompanying drawings shall be interpreted as illustrative and not in a limiting sense.

I claim:

30 1. In a switch, line terminals, a switch cartridge including terminal engaging elements, a hinge including a swingable socket, a portion on the cartridge loosely engaging in said socket, a stop on the cartridge limiting its descent into the socket, a lug on the socket and a recess in the stop snugly engaging the lug and adapted to more perfectly align the engaging elements with the line terminals than would be possible with the loose fit between the cartridge and the socket.

35 2. In a switch, line terminals, a switch cartridge including terminal engaging elements, and a fibrous portion, a hinge including a swingable socket composed of metal, said fibrous portions of the cartridge loosely engaging in said metal socket, a metallic stop on the cartridge, a metal lug associated with the socket and a recess in the stop snugly engaging the lug and adapted under all conditions to more perfectly align the engaging elements with the line terminals than would be possible with the necessarily loose fit between the fibrous portion of the cartridge and the metallic socket.

40 3. In a switch, line terminals, a switch cartridge including terminal engaging elements, a hinge including a swingable socket, a portion on the cartridge loosely engaging in said socket, a stop on the cartridge limiting its descent into the socket, a lug on the socket and a recess in the stop snugly engaging the lug and adapted to more perfectly align the engaging elements with the line terminals than would be possible with

the loose fit between the cartridge and the socket, and a set of guiding horns associated with the hinge for further guiding the cartridge said horns being positioned above said stop when the switch is closed to hold the same substantially immovable.

4. In a switch, line terminals, a switch cartridge including terminal engaging elements, and a fibrous portion, a hinge including a swingable socket composed of metal, said fibrous portions of the cartridge loosely engaging in said metal socket, a metallic stop on the cartridge, a metal lug associated with the socket and a recess in the stop snugly engaging the lug and adapted under all conditions to more perfectly align the engaging elements with the line terminals than would be possible with the necessarily loose fit between the fibrous portion of the cartridge and the metallic socket, and a set of guiding horns associated with the hinge for further guiding the cartridge said horns being positioned above said stop when the switch is closed to hold the same substantially immovable.

In testimony whereof, I have signed my name to this specification this 19th day of January, 1929.

THEODORE BIRKENMAIER.
